Primary Examiner—Bruce W. Dunkins*Assistant Examiner*—Jeffrey Asch*Attorney, Agent, or Firm*—Fitch, Even, Tabin & Flannery[57] **CLAIM**

The ornamental design for a coupon distribution stand, as shown and described.

DESCRIPTION

FIG. 1 is a front and right side perspective view of a coupon distribution stand showing my new design, the left side being a mirror image thereof;

FIG. 2 is a top plan view on an enlarged scale;

FIG. 3 is a front elevational view;

FIG. 4 is a rear elevational view; and,

FIG. 5 is a bottom plan view thereof on an enlarged scale.

FIG. 1

FIG. 2

FIG. 3

FIG. 4

FIG. 5
